H. E. JACKSON.
WAGON BED RAISER.

No. 423,771.

Patented Mar. 18, 1890.

FIG. V.

UNITED STATES PATENT OFFICE.

HAMPTON E. JACKSON, OF WILSON, OHIO.

WAGON-BED RAISER.

SPECIFICATION forming part of Letters Patent No. 423,771, dated March 18, 1890.

Application filed June 18, 1889. Serial No. 314,173. (No model.)

To all whom it may concern:

Be it known that I, HAMPTON E. JACKSON, a citizen of the United States, and a resident of Wilson, in the county of Adams and State 5 of Ohio, have invented certain new and useful Improvements in Wagon-Bed Raisers, of which the following is a specification.

My invention is an improvement in devices for raising or lifting the bed or body of a 10 wagon off its running-gear, for suspending it from the joists or rafters of a barn or shed, and for lowering it to any desired position.

The construction of my device is such as to preclude the possibility of the bed tipping 15 to one side or the other side when raised or lifted from its supports on the bolsters.

In order that my invention may be fully understood, I will proceed to describe it with reference to the accompanying drawings, in 20 which—

Figure I is a front elevation of the windlass. Fig. II is a top view thereof. Fig. III is a rear view of the same. Fig. IV is an end elevation. Fig. V is a side elevation showing 25 the whole raising device, a portion of the side of the wagon bed or body being omitted.

1 are the rafters or joists of a barn or shed, and 2 a wagon bed or body suspended therefrom, having a floor 3, end gates 4 5, and 30 cross-piece 6.

7 are pulleys secured to the joists or rafters by means of loops 8. Free to run over these pulleys when being wound up or paid out is a cord 9, having one end formed with 35 a loop 10, engaging the cross-piece 6 on the front end of the wagon bed or body and the other end secured to my improved winding apparatus or windlass, which I will now describe.

40 11 is a clamp-frame, formed integral with a central top opening 12, downwardly-inclined arms 13, outturned portions 14, vertical portions 15, and inturned portions 16. The outturned portions provide bearings in which 45 work the clamp-bolts or thumb-screws 17 for holding the frame in position on the rear end of the floor 3 of the wagon bed or body, the inturned portions extending beneath the floor.

Secured on each side of the top opening of 50 the frame are quarter-circle plates or wings

18, having recesses 19. These plates or wings are located at one side of the center of the frame, so as to form, in connection with the latter, the slots or openings 20 and the orifices 21, to which the slots or openings lead.

55 22 is a shaft formed integral with a winch or handle 23, passed through the slots or openings and seated in the orifices which form bearings therefor. The shaft is provided with a central stud or pin 24, friction-disks or brake-wheels 25, and ratchet-wheel 26. The winding-cord 9 is secured to the stud or pin.

27 is a spring brake-lever, bent or curved as shown, formed with a bifurcated or forked 65 inner end 28, adapted to be inserted in the top opening and engage the frame at either end of the opening. The brake-lever is also formed with a recess or excavation 29, to receive the edge or periphery of a friction-disk 70 or brake-wheel, and with a handle 30 by which the operator controls the rotation of the disk or wheel. The ratchet-wheel is formed with teeth 31, with which the pawl 32, pivoted to the frame, is adapted to engage to prevent the shaft turning back until the pawl is disengaged from the teeth.

The clamp-bolts or thumb-screws, as well as securing the clamp-frame to the floor, have a tendency to hold the latter together.

80 The provision of the pawl-and-ratchet wheel enables the operator to lock the shaft when the bed or body is raised to a sufficient height.

The brake device serves as a hand-steadier 85 in raising and lowering the bed or body, and operates as a brake to regulate the descent of the bed or body when lowering it to place.

The brake-wheels or friction-disks confine the cord in winding and unwinding.

90 The whole device is readily separable for packing and shipment.

Having thus described my invention, the following is what I claim as new therein and desire to secure by Letters Patent:

1. The clamp-frame 11, formed integral with top opening 12, downwardly-inclined arms 13, outturned portions 14, vertical portions 15, and inturned portions 16, substantially as described.

100

2. The combination of the clamp-frame 11, clamp-bolts 17, and plates 18, formed with recesses 19, the clamp-frame and plates being arranged to form openings 20 and orifices 21 between them, substantially as described.

3. The combination of the clamp-frame 11, the plates 18, having recesses 19, the shaft 22, having handle 23, stud 24, and ratchet-wheel 26, and the pawl 32, substantially as described.

4. The combination of the clamp-frame 11, the plates 18, having recesses 19, the shaft 22, having friction-disks 25, and the brake-lever 27, formed with bifurcated inner end 28, and recess 29, and handle 30, substantially as described.

5. The combination of the clamp-frame having top opening 12, the shaft 22, having a friction-disk, and the spring brake-lever 27,

formed with bifurcated inner end 28, recess 29, and handle 30, substantially as described.

6. A wagon-bed raiser comprising the pulleys 7, the cord 9, formed with a loop 10, the clamp-frame 11, the clamp-bolts 17, the plates 18, having recesses 19, the shaft 22, having stud 24, the ratchet-wheel 26, and the pawl 32, substantially as described.

7. A wagon-bed raiser comprising the pulleys 7, the cord 9, formed with a loop 10, the clamp-frame 11, the clamp-bolts 17, the plates 18, having recesses 19, the shaft 22, having stud 24, the friction-disks 25, the ratchet-wheel 26, the pawl 32, and the brake-lever 27, substantially as described.

HAMPTON E. JACKSON.
